CLAIM

The ornamental design for faucet stream straightener as shown and described.

DESCRIPTION

The patent or application file contains at least one drawing executed in color. Copies of this patent or patent application publication with color drawing(s) will be provided by the Office upon request and payment of the necessary fee.

1. Faucet stream straightener

2. Faucet stream straightener

1.1 : Perspective

1.2 : Right

1.3 : Top

1.4 : Perspective

1.5 : Bottom

1.6 : Front

1.7 : Left

1.8 : Back

1.9 : Cross sectional

2.1 : Perspective

2.2 : Right

2.3 : Top

2.4 : Perspective

2.5 : Bottom

2.6 : Front

2.7 : Left

2.8 : Back

2.9 : Cross sectional

The red colored parts in design 2 are not part of the claimed design; View 1.9 and 2.9 (cross-sectional views) are for explanation of the other views only and do not define the scope of protection; For China only: 1. The name of the product incorporating the design is: faucet stream straightener; 2. Use of the product: for straightening stream, as fluid distribution equipment; 3. The key feature of the design lies in the shape of the product; 4. The figure or view to be designated for best showing the key feature of the design is: Fig. 1.1 of Design No. 1.
